[57] CLAIM

The ornamental design for a lipstick holder, as shown and described.

DESCRIPTION

FIG. 1 is a side elevation of the lipstick holder, the opposite side being identical thereto;
FIG. 2 is a front elevational view thereof, the opposite side being identical thereto;
FIG. 3 is a top plan view of FIG. 1; and,
FIG. 4 is a bottom plan view of FIG. 1.

FIG. 1
